ALFRED COTTON, OF ST. LOUIS, MISSOURI, ASSIGNOR TO HEINE BOILER COMPANY,
OF ST. LOUIS, MISSOURI, A CORPORATION OF MISSOURI.

METHOD AND APPARATUS FOR PRODUCING HEADERS.

Application filed March 27, 1924. Serial No. 702,279.

To all whom it may concern:

Be it known that I, ALFRED COTTON, a citizen of the United States, residing at St. Louis, Missouri, have invented a certain 5 new and useful Improvement in Methods and Apparatus for Producing Headers, of which the following is a full, clear, and exact description, such as will enable others skilled in the art to which it appertains to make 10 and use the same.

This invention relates to headers of the kind that consist of a hollow member constructed from a welded or drawn tube of circular or oval shape in cross section that 15 is deformed by pressure applied externally to the front and rear sides and to the lateral sides of the tube in such a way as to produce a header having alternately-arranged valleys and ridges on each of its lateral sides 20 and alternately-arranged valleys and ridges on its front and rear sides.

In my pending application for Patent Serial No. 655,666, filed August 4, 1923, I have disclosed a machine for producing 25 such a header by deforming a tube by a rolling operation and simultaneously forming flat faces on the front and rear sides of the tube that constitute seats for the hand hole covers of the header and seats for the tubes to which the header is connected, said machine comprising four right-angularly-disposed rolls that act on the exterior of the tube and deform it progressively, and a collapsible mandrel for internally supporting 30 the portions of the front and rear sides of the tube that are flattened to form hand hole cover seats and tube seats.

The main object of my present invention is to provide a method of producing a header 40 of the general type referred to which makes it possible to use sand or other suitable granular material to internally support a tube that is being deformed progressively by external rolls, two of which are provided 45 with pressing portions that form sharp-angled, flat-faced indentations in the front and rear sides of the tube that constitute seats for the hand hole covers of the header and seats for the ends of the tubes to which 50 the header is connected.

Another object is to provide a practicable apparatus or machine for practicing my method.

In a header of the kind above referred to the cross-sectional area of the header is 55 smaller at all points along its length than the cross-sectional area of the tube from which it is formed, owing to the fact that the lateral sides of the header are made up of opposed inwardly-pressed portions and 60 opposed outwardly-bulged portions, and the front and rear sides of the header are also made up of inwardly-pressed portions and outwardly-bulged portions that have flat-faced indentations produced by pressing portions 65 on the front and rear rolls. Consequently, in manufacturing such a header it is not feasible to completely fill a tube with sand or the like and then deform the tube progressively by passing it between two 70 pairs of right-angularly-disposed rolls that press opposed portions of the tube inwardly, because the sand, which is virtually incom-75 pressible, would offer so great a resistance to the inward pressure of the rolls that the bulged portions of the tube would not be symmetrical and the pressing portions on the front and rear rolls would be apt to shear through the tube, instead of simply pressing sharp-angled, flat faces in the tube. 80 I have discovered, however, that granular material such as sand can be used success-85 fully for internally supporting a tube that is being deformed progressively by rolls, some of which are provided with pressing portions that form flat seat faces in the tube, if the granular material is arranged in the tube in such a manner that it is capable of flowing longitudinally of the tube away from the portion of the tube be-90 ing acted on by the deforming rolls, but will offer sufficient lateral resistance to the inward pressure exerted on the tube by the rolls, to cause the pressing portions on the front and rear rolls to form flat-faced, 95 sharp-angled indentations in the tube without subjecting the tube to abnormal strains.

A comparatively small resistance to longi-100 tudinal flow of the granular material in the tube is sufficient to cause said granular ma-105 terial to offer an enormous resistance laterally. Accordingly, I propose to internally support a tube that is being deformed pro-gressively by rolls, some of which are pro-vided with flat-faced pressing portions, by filling the tube with sand or other suitable

granular material for some distance above the point where the rolls are acting on the tube, so as to virtually form a "head" of sand in the tube that impose a load on the sand which fills the portion of the tube being acted upon by the rolls, and maintaining this "head" constant, or practically so, while the tube is being deformed and fed through the rolls. When the rolls are revolving the 10 column of sand or other granular material in the tube that extends upwardly above the portion of the tube being acted upon by the rolls will flow upwardly longitudinally of the tube and relative to the tube as the tube 15 is deformed. Consequently, the friction of said column of sand against the sides of the tube, as well as the weight of said column, is used to resist longitudinal flow of the sand that fills the portion of the tube which is 20 being engaged by the rolls. The greater the area of contact between the sand and the tube, the greater is the friction. The greater the height of the sand above a given point, the greater is the pressure of the sand against 25 the tube at that point, and this increases the friction between the sand and the tube. Since with a cylindrical or oval tube such as is used in practicing my method the area of contact varies as the length of the tube, the 30 friction varies as the height of the sand above the rolls. After the requisite volume of the column of sand in the tube has been ascertained, it is a simple matter to maintain said column constant, and when the thickness 35 of the tube used to form the header is changed, or when the temperature of the tube or the material of which it is constructed is changed, the column of sand in the tube can be modified to satisfy the changed 40 conditions.

Various means can be used for maintaining a column of granular material in the tube of sufficient volume to insure symmetrical bulged portions on the tube and to eliminate the possibility of the pressing portions 45 on the front and rear rolls cutting through the parts of the tube in which the flat seat faces are being formed, but the simplest way of accomplishing this is to fill the tube with 50 said or other suitable granular material up to a certain approximate point above the zone of the tube on which the rolls first act and then feed additional sand into the tube as the deforming operation proceeds, at such 55 a rate as to keep the height of the column of sand above the rolls uniform, or substantially uniform.

Figure 1 of the drawings is a vertical transverse sectional view of one form of apparatus that can be used for practicing my method; and

Figure 2 is a perspective view of a header produced by said apparatus.

Referring to the drawings, α designates a 60 metal tube of oval or circular shape in cross

section that is adapted to be fed between two pairs of rolls arranged at right angles to each other and of such shape that they will convert said tube into a header of the kind shown in Figure 2 which has lateral 70 sides, each of which is made up of a series of valleys 1 arranged between a series of ridges or outwardly-bulged portions 2 and front and rear sides, each of which is made up of a series of bulged portions 3 arranged in alternate relation with a series of valleys 4, the valleys 4 in the front and rear sides of the header extending transversely of same and being of greater length than the width of the bulged portions 3 on the front and 75 rear sides of the header. Indentations 5 and 6 are formed in the front and rear sides of the tube during the deforming operation so as to form sharp-angled, flat-faced seats for handle hole covers and for the tubes to 80 which the header is to be connected, it being understood that the flat-faced indentations on the rear side of the header are adapted to have holes cut in same to receive said tubes, and that the flat-faced indentations 85 on the front side of the header are adapted to have hand holes formed in same. Obviously, the shape and area of the indentations 5 and 6 are immaterial. In the header 90 herein shown the indentations 5 and 6 above referred to are disposed at a slight angle to the vertical and are produced by pressing portions 5^a and 6^a on the front roll A and rear roll B of the machine. I have not 95 illustrated the side rolls that act on the sides of the tube, as my present invention relates to a novel method of internally supporting the portion of the tube acted on by the flat-faced pressing portions of the front and rear rolls, it being unnecessary to internally support the portions of the tube acted upon by the side rolls. Suffice it to say that the machine or apparatus in which the tube α is 100 deformed comprises one pair of rolls composed of a front roll A and a rear roll B, each of which is provided with flat-faced 105 pressing portions 5^a and 6^a, and a second set of side rolls arranged at right angles to the front and rear rolls and of the construction shown in my pending application previously 110 referred to. Each of the various rolls above referred to is mounted on a carriage C that can be moved towards and away from an open space at the center of the machine in 115 which the tube α is arranged vertically, and means is provided for rotating said rolls after they have been moved into engagement with the tube so as to progressively deform 120 said tube and feed it downwardly between said rolls, the tube being maintained in an upright position by an annular guide D, as shown in Figure 1.

The tube α is closed at its lower end, as shown in Figure 1, so that it can be partly 125 filled with sand or other suitable granular 130

- material E that is used to internally support the portions of the tube acted upon by the pressing portions 5^a and 6^a on the front and rear rolls, and thus cause said pressing portion to form sharp-angled, flat seat faces 5 and 6 in the front and rear sides of the tube. After the tube α has been arranged in an upright position between the rolls of the machine, sand or other granular material 10 E is allowed to flow into said tube from a spout 7 that projects downwardly into the tube from a sand hopper 8. The sand is allowed to flow from the spout 7 until it stops, owing to the sand assuming its natural 15 angle of repose from the lower end of said spout. The rolls of the machine are then moved inwardly into engagement with the tube α , as shown in Figure 1, and thereafter said rolls are set in operation so as to press 20 opposed portions of said tube inwardly and feed said tube downwardly, as described in my pending application previously referred to. As the tube α passes downwardly more sand flows into same from the spout 7, 25 thereby maintaining a practically constant head or column of sand in the tube above the point at which the rolls are acting on the tube. In order that the column of sand in the portion of the tube above the zone of the 30 tube on which the rolls are acting may be varied, the hopper 8 from which the spout 7 leads is mounted in such a way that it can be raised and lowered with respect to the rolls of the machine, the hopper of the 35 machine herein shown being mounted on brackets 9 that are sustained by co-operating elements 10 adjustably mounted on uprights 11. In an apparatus of the kind above described sand or the like is fed into the tube α automatically and is automatically maintained at such a height with relation to the rolls that the sand will accommodate itself to the changing shape of the tube as it becomes a header, but without liability of 40 producing unsymmetrical, bulged portions on the tube or causing the pressing portions on the front and rear rolls to shear through the tube.
- While I have herein illustrated my method as being carried out in an apparatus in which the feeding of the sand or other granular material into the tube α is automatically controlled by using the angle of 45 repose of the sand at the upper end portion of the column to cut off the escape of sand from the supply spout 7, I wish it to be understood that my broad idea contemplates using any suitable means for feeding sand or other granular material into the tube that is being deformed and for automatically controlling the feed of said sand in such a way as to create and maintain a column of sand or the like in the tube, that is free to flow upwardly longitudinally of the tube when the deforming rolls are acting
- on the tube, but which offers sufficient lateral resistance to the inward pressure exerted on the tube by the rolls to insure the pressing portions on the front and rear rolls forming flat-faced, sharp-angled indentations in the tube that will form satisfactory seats for the hand hole covers of the headed and the ends of the boiler tubes to which the header is connected.
- It is often desired to carry the deformation of the tube to a point so near its upper end that there would not be a sufficient head of sand above the rolls. In other words, it is often necessary to continue the formation of the tube and handhole seats in the tube to such a point towards the upper end of the tube, that the upper end would be fed downward toward the rolls until it was so much below the lower end of the spout 7 that the sand would escape from said spout. 50 In such instances it is necessary to connect a temporary extension to the upper end of the tube α . This can be accomplished easily by connecting a tubular member to the upper end of the tube by clamps, spot-welding, etc., or said tubular member may be simply telescoped inside or outside of the tube α . At the completion of the deforming operation said temporary extension is removed from the header.
- Having thus described my invention, what I claim as new and desire to secure by Letters Patent is:
1. A method of producing a header, which consists of progressively deforming a tube 100 by rolls that press opposed portions of the tube inwardly and simultaneously form seat faces in the tube, and internally supporting the tube during the deforming operation by a column of granular material in the tube that is permitted to flow freely longitudinally of the tube but which imposes a sufficient load on the granular material in the zone of the deforming rolls to insure the formation of seat faces on the 105 tube that are sharp-angled and flat.
2. A method of producing a header, comprising deforming a tube progressively by external pressure exerted on the tube by 110 rolls which form valleys and ridges in opposed portions of the tube and also form indentations in said opposed portions, internally supporting the tube during the deforming operation by a column of granular material in the tube that completely fills 115 the zone of the tube acted upon by said rolls and the adjacent portion of said tube, and which is permitted to flow freely longitudinally of the tube, and maintaining said column practically constant as the deforming operation proceeds, thereby causing the rolls to act uniformly on all portions of the tube and without liability of shearing the tube at the points where the indentations 120 are formed in same.

3. A method of producing a header, comprising deforming a tube progressively by means of rolls that press opposed portions of the tube inwardly and simultaneously

5 form indentations in the tube, filling the tube with granular material to a certain height above the zone on which the rolls are acting so as to form a column of granular material in the tube that offers sufficient 10 lateral resistance to the inward pressure of the rolls to insure the formation of sharp-angled, flat-faced indentations, and feeding additional granular material into the tube as the deforming operation proceeds so as 15 to maintain said column practically constant.

4. A method of producing a header, comprising feeding a tube between opposed rolls, causing said rolls to press opposed portions 20 of the tube inwardly and also form flat-faced indentations in the tube, internally supporting the tube during the deforming operation by a column of granular material that is permitted to flow freely longitudinally 25 of the tube away from the zone of the tube on which the rolls are acting, and maintaining said column practically constant during the deforming operation, thereby maintaining a practically uniform load on 30 the granular material that fills the portion of the tube on which the deforming rolls are acting.

5. A method of producing a header, comprising deforming a tube progressively by 35 rolls that form inwardly-pressed portions and outwardly-bulged portions in the tube that contain indentations which are used to form seats for hand hole covers and boiler tubes, and internally supporting the tube 40 during the deforming operation by a mass of granular material in the tube that is free to flow longitudinally of the tube in one direction and which exerts a practically uniform load on the granular material which 45 fills the zone of the tube on which the rolls are acting.

6. A method of producing a header, comprising deforming a tube progressively by rolls that form inwardly-pressed portions 50 and outwardly-bulged portions in the tube that contain flat-faced indentations that are used as seats for the hand hole covers of the header and the boiler tubes to which the header is connected, internally supporting the portion of the tube being acted upon by said rolls by a mass of granular material that completely fills the zone of the tube in proximity to said rolls, and causing said granular material to offer a 55 practically uniform lateral resistance to the pressure of the rolls as the deforming operation proceeds.

7. A method of producing a header, comprising arranging a tube in an upright position 60 between rolls, causing said rolls to act

on the tube in such a way as to feed the tube downwardly and simultaneously form inwardly-pressed portions and outwardly-bulged portions in the tube that contain flat-faced indentations, filling the tube with 70 granular material prior to the beginning of the deforming operation up to such a height above the zone of the rolls as to create a column of granular material in the tube that offers the requisite lateral resistance to the 75 inward pressure of the rolls to insure uniform deformation of the tube, and maintaining the height of the said column with respect to the rolls practically constant during the deforming operation by feeding additional granular material into the tube as 80 the tube passes downwardly between the rolls.

8. An apparatus for producing a header, comprising opposed rolls between which a 85 tube is adapted to be arranged, said rolls being of such shape that they will press opposed portions of the tube inwardly and also form flat-faced indentations in the tube as the tube travels lengthwise between the 90 rolls, and means for causing the tube to be internally supported during the deforming operation by a mass of granular material that is permitted to flow relatively to the tube in one direction and which exerts a 95 substantially uniform lateral resistance to the inward pressure exerted on the tube by the rolls.

9. An apparatus for producing a header, comprising a pair of rolls between which a 100 tube is adapted to be arranged and provided with co-operating portions that deform the tube progressively, feed it lengthwise between the roll and form flat-faced 105 indentations in the tube, and means for introducing granular material into the tube at such a rate as the deforming operation proceeds as to maintain in the tube a column of granular material that offers a substantially 110 uniform lateral resistance to the inward pressure exerted on the tube by the rolls.

10. An apparatus for producing a header, comprising opposed rolls adapted to have a tube arranged in a vertical position between the same and provided with co-operating portions that deform the tube progressively, feed it downwardly between the rolls and also form flat-faced indentations in opposed portions of the tube, a hopper arranged above said rolls for holding granular material, and a spout leading from said hopper and projecting downwardly into said tube for automatically supplying granular material to the tube, for the purpose described.

11. An apparatus for producing a header, comprising opposed rolls adapted to have a tube arranged in a vertical position between the same and provided with co-operating portions that deform the tube progressively,

feed it downwardly between the rolls and also form flat-faced indentations in opposed portions of the tube, a hopper arranged above said rolls for holding granular material, a spout leading from said hopper and projecting downwardly into said tube for automatically supplying granular ma-

terial to the tube, for the purpose described, and means for enabling the discharge end of said spout to be raised and lowered with respect to the rolls, for the purpose described.

ALFRED COTTON.
